UNITED STATES PATENT OFFICE.

JACOB AARON HERMAN, OF NEW YORK, N. Y.

MATERNITY-GOWN.

1,043,232.

Specification of Letters Patent.

Patented Nov. 5, 1912.

Application filed November 11, 1911. Serial No. 659,787.

To all whom it may concern:

Be it known that I, JACOB AARON HERMAN, a citizen of the United States, residing at New York city, in the county and State 5 of New York, have invented certain new and useful Improvements in Maternity-Gowns, of which the following is a specification.

This invention relates to apparel, and 10 more especially it is an adjustable gown; and its object is to provide for adjusting the gown forward of the sleeves and at either side of the front opening in such manner that a trim appearance can be maintained.

15 In order to carry out this object the invention consists more particularly in the specific manner of forming the plaits so as to preserve the beauty of the garment under varying conditions due to its adjustment.

20 That is to say, below the waist line the plaits are made permanent or fixed as by stitching them along their edges, the stitching preferably reinforced at the waist line by the socket members of the fastening or 25 adjusting devices hereinafter described; while above the waist line the plaits are left free or loose in order to produce a fullness of cloth which fits the wearer's figure at all times and adapts itself to varying conditions.

30 My preferred manner of carrying out this invention is set forth in detail in the following specification and claim, and illustrated in the drawing wherein—

35 Figure 1 is a perspective view representing the gown when adjusted to its smallest size; Fig. 2 is a perspective view representing the gown when adjusted to its largest size; Fig. 3 is a perspective view representing the gown when again adjusted to its 40 smallest size and showing the front open in order that a mother can nurse a child; Fig. 4 is a section on the waist line of the gown when adjusted as shown in Fig. 1; Fig. 5 is an enlarged detailed section of certain parts 45 adjusted as in Fig. 4; Fig. 6 is a section on the waist line of the gown when adjusted as shown in Fig. 2; Fig. 7 is an enlarged detailed section of certain parts adjusted as in 50 Fig. 6.

This improved garment is composed of a waist 1 and skirt 2, and these parts may be integrally connected or stitched together. The waist may have sleeves as shown, or 55 not, but this detail does not enter into the invention. By preference it is open down

its front to the waist line, the right side 3 having hooks 4 and the left side 6 having eyes 5 or other suitable fastening devices, so that the garment may be closed as seen in 50 Figs. 1 and 2 or opened as seen in Fig. 3 when the mother desires to nurse her child. The opening in the front may be continued below the waist line to the bottom of the skirt 2 if desired, but this detail is unimportant and is not illustrated. Obviously the hooks and eyes 4 and 5 might be replaced by other fastening devices forming no part of the present invention.

The peculiarity of this garment consists 70 in forming each front gore or side section 3 and 6 rather full just above the waist and folding the material in two or more loose plaits 7 and 8 which always run out to nothing below the bust, are not very pronounced 75 when the garment is contracted as seen in Fig. 1, are still less so when the garment is expanded as seen in Fig. 2, and would disappear entirely if the garment were further enlarged than anywhere illustrated in the 80 drawing. In conjunction with the formation of these plaits, the skirt is formed with an equal number of what I will call "fixed" 85 plaits 9, because, although they are capable of opening as wide as the lower ends of the plaits 7 and 8, their extreme edges are fixed as by means of stitching or otherwise but certainly by the means set forth below; and these plaits 9 align with the plaits 7 and 8 and are by preference extended from the 90 waist line to the bottom of the garment about as indicated.

While any suitable form of adjusting devices may be employed, I prefer studs 13 and sockets 14 and in any event they will 95 be located along the waist line 12. Where each side of the garment has two plaits 7 and 8, there will be two series of studs 13 with perhaps five studs in each series as best seen in Fig. 5, and the shanks of the 100 studs will be attached to the material in any suitable manner with their heads outside the garment. Coacting with the studs in each series will be a socket 14 as well shown in Figs. 5 and 7, and this socket may 105 be attached to the material in any suitable manner but will by preference define the upper end of the fixed plait 9 in the skirt whether said plait is stitched from that point downward or not, as a stud is well 110 adapted to do. A garment thus constructed may be contracted as seen in Fig. 1, and

will be made in sizes so that it is at that time well adapted to the normal female figure. When now it is desired to adjust the size of the garment at the waist line and immediately above and below, the socket member 5 14 is removed from the innermost stud 13 as seen in Fig. 5 and moved along to the next stud and this is repeated at the opposite side of the front opening. When occasion occurs requiring a further adjustment, 10 the operation is repeated and the socket is moved to the next stud at each side of the front opening. Finally the adjustment will be carried to the point illustrated in Fig. 7 where the socket engages the last stud 13 of 15 the series. The plaits 9 in the skirt 2 are now opened to their widest extent, and would open no farther if the stud and socket members were entirely disengaged; 20 and the plaits 7 and 8 of the waist 1 are opened nearly to their largest extent, their folds 10 which were more or less pronounced in Figs. 4 and 6 having now been reduced to a minimum, and it is clear that these 25 would disappear entirely if the stud and socket were disengaged. While this expedient may be resorted to if the bust became very large, ordinarily the gown will be proportioned properly so that the adjustment 30 need not be carried beyond the innermost stud 13 in each series, and therefore the fixed plait 9 in the skirt is continued upward in appearance just past the waist line 12 into each of the waist plaits 7 and 8, and immediately begins to fade away so that in any 35 event it disappears beneath the bust. I consider it of great advantage to form this garment with the points or lines of adjustment between the arms and the front line, 40 both because it is preferable to provide fullness in maternity gowns at the front rather than at either side or in the back, and because the fit of the garment, the lines of its plaits, and the continuity of its figure if it 45 be of figured goods will be maintained in this manner whereas they would be de-

stroyed if the adjustment were at other places. But the gist of my invention lies in fixing the edges of the skirt plaits and leaving the waist plaits loose or free, while having them coincident with each other so that the gown may be enlarged from time to time as described above. 50

In connection with this improved gown I preferably make use of a belt 15 secured as 55 at the points 16 to the back 11 of the gown and having a buckle 17 or other device by means of which its free ends may be brought together and fastened at the front; and the use of such a belt will cover the adjusting 60 devices 13 and 14 although they may be of such character that they will not be at all unsightly if the belt be entirely omitted as some wearers prefer.

Throughout this specification I have pur- 65 posely avoided details as to the material, sizes, and proportions of parts, as these are evidently unimportant.

I repeat that other fastening devices than hooks and eyes might be employed along the 70 front, and other adjusting devices than studs and sockets might be employed around the waist line.

What is claimed as new is:—

The herein described adjustable gown 75 comprising a skirt and a waist, the skirt having fixed plaits merging into loose plaits in the waist forward of the arms, and adjusting devices for each plait consisting of one member permanently fixed to the edge 80 of the skirt plait and a series of members on the outer face of the material between plaits, with any of which members said fixed member may engage, all said devices being located along the waist line and adapted to 85 be concealed by the belt.

In testimony whereof, I affix my signature, in the presence of two witnesses.

JACOB AARON HERMAN.
